UNITED STATES PATENT OFFICE.

LEO GUDEMAN, OF NEW YORK, N. Y.

DESIGN FOR AN ILLUMINATED ROSETTE.

40,740.

Specification for Design.

Patented June 21, 1910.

Application filed April 5, 1910. Serial No. 553,672. Term of patent 7 years.

To all whom it may concern:

Be it known that I, LEO GUDEMAN, a citizen of the United States of America, residing at New York, in the county of New York and State of New York, have invented a new, original, and ornamental Design for an Illuminated Rosette, of which the following is a specification, reference being had to the accompanying drawing, forming part hereof.

The drawing is a perspective view of an illuminated rosette, showing my new design.

I claim:

The ornamental design for an illuminated rosette, as shown.

LEO GUDEMAN.
